ABSTRACT: Alkyl cyanide compounds are disclosed as addition agents for improving the liquid-liquid extraction of alkyl lead compounds from mixtures thereof with organometallic complexes with an extraction medium comprising iso-octane.

**EXTRACTION OF ALKYL LEAD COMPOUNDS FROM
ORGANOMETALLIC COMPLEXES**

BACKGROUND OF THE INVENTION

1. Field of Invention

This invention relates to the liquid-liquid extraction of alkyl lead compounds from mixtures thereof with organometallic complexes.

2. Description of Prior Art

Electrolytic syntheses of organometals are known. Calingaert and Mead disclosed tetraalkyl lead formation at a lead cathode by electrolyzing a catholyte consisting of an alkyl halide in either alcoholic caustic (Calingaert in U.S. Pat. No. 1,539,297) or aqueous caustic containing casein (Mead in U.S. Pat. No. 1,567,159). Besides the cathodic processes, anodic oxidations have also been employed to produce organometallics, as for example by Hein et al. *Z. anorg. Allgem. Chem.* 141, 161 (1924) who obtained tetraethyl lead by electrolyzing sodium zinc triethyl at a lead anode, and by Ziegler in British Pat. No. 814,609 (1959) who discloses synthesis of Group II-V metal alkyls by electrolyzing a complex aluminum alkyl at an anode composed of the Group II-V metal. Numerous other references disclose similar processes.

Iso-octane has been disclosed as an extraction medium for the liquid-liquid extraction of alkyl lead compounds from mixtures thereof with organometallic complexes. Though extraction occurs, there are problems which are vexing. One of the worst is the emulsification of the iso-octane, so that good recovery is difficult.

SUMMARY OF INVENTION

According to this invention an alkyl cyanide is utilized to improve the liquid-liquid extraction separation of alkyl lead compounds from mixtures thereof with organometallic complexes with an extraction medium comprising iso-octane.

DETAILED DESCRIPTION

In carrying out the process of the invention, the alkyl cyanide can be added to the organometallic complex and alkyl lead mixture and the liquid-liquid extraction then accomplished by adding iso-octane to said mixture. When this method is followed there is no emulsification of the iso-octane and the separation is markedly improved. When the same method is followed but no alkyl cyanide is added, emulsification of the iso-octane occurs and the recovery of the alkyl lead compound is more difficult. The following example illustrates the process of this invention.

EXAMPLE

To determine the extraction process, 80 cc. of $KAlEt_2Cl_2$ and 80 cc. of acetonitrile were mixed and tetraethyl lead was then added to the mixture. Various concentrations of tetraethyl lead were used. These samples were then each ex-

tracted with 40 cc. of iso-octane, and then analyzed chromatographically.

The following table illustrates the results.

TABLE

TEL Recovery ¹ at 50°C.			
	TEL added	TEL recovered	% recovered
10	0.4 cc	0.366	91.4
	0.8 cc.	0.758	94.7*
	1.2 cc.	1.103	91.9
	1.6 cc.	1.458	91.15
Average =91.48*			

¹Thrown out in averaging.

Extraction: 80 cc $KAlEt_2Cl_2$
80 cc CH_3CN extracted with 40 cc Iso-octane
+TEL

²Average $K_p = C_{iso-octane}/C_{complex} = 43.1$

The alkyl cyanides suitable for this process include those which have alkyl groups ranging from about one to about three carbon atoms. Examples of such compounds are acetonitrile, propionitrile and n-butyronitrile.

The concentration of alkyl nitrile in said system for best results should range from about 20 to about 80 volume percent and preferably between about 40 and about 50 volume percent.

Having thus described the invention by providing specific examples thereof, it is to be understood that no undue limitations or restrictions are to be drawn by reason thereof, and that many variations and modifications are within the scope of the invention.

What is claimed is:

1. In the liquid-liquid extraction of alkyl lead compounds from mixtures thereof with an organometallic complex $KAlEt_2Cl_2$ with an extraction medium comprising iso-octane, the method of reducing the emulsification of said mixture which comprises adding thereto an effective amount of an alkyl cyanide.
2. The method of claim 1 wherein said alkyl lead compound is tetraethyl lead.
3. The method of claim 1 wherein the alkyl group of said alkyl cyanide contains from about one to about three carbon atoms.
4. The method of claim 3 wherein said alkyl cyanide is acetonitrile.
5. The method of claim 1 wherein said alkyl cyanide is present in concentrations of from about 20 to about 80 volume percent.
